UNITED STATES PATENT OFFICE.

WILLIAM A. KNAAPP, OF WASHINGTON, DISTRICT OF COLUMBIA.

DROP-HAMMER.

1,327,331.

Specification of Letters Patent.

Patented Jan. 6, 1920.

Application filed November 23, 1918. Serial No. 263,917.

To all whom it may concern:

Be it known that I, WILLIAM A. KNAAPP, a citizen of the United States, and resident of Washington, District of Columbia, have 5 invented certain new and useful Improvements in Drop-Hammers, of which the following is a specification.

My invention is designed to provide a drop hammer, the stroke of which will be 10 under the complete control of the operator, enabling him at will to get a length of stroke or drop of the hammer exactly suited to his needs.

The invention consists in the features and 15 combination and arrangement of parts hereinafter described and particularly pointed out in the claims.

In the accompanying drawings:

Figure 1 is a side elevation of a drop hammer embodying the invention.

Fig. 2 is a view looking from the left of Fig. 1 with the belts in section.

Fig. 3 is a detail of the sheath and drum associated therewith.

Fig. 4 is a sectional view of the sheath.

In these drawings 1 indicates a drop hammer, 2 a band or strap attached thereto for lifting it, 3 a drum over which the band passes and 4 the handle by which the operator 20 controls the operation of the hammer.

The drum 3 is fixed to the shaft 5 which is journaled in bearings 6 of the frame and carries a pulley 7 driven by a belt 8 by which arrangement the drum 3 is rotated 35 constantly in one direction.

Associated with this drum 3 is a sheath or controller 9. This may assume different forms but in the particular form shown it consists of arms 10 loosely mounted on the

shaft 5 at the sides of the drum 3 and carrying a cross piece 11 provided with a channel or space 12 receiving the band 2. This sheath when in normal position, shown in

Fig. 1, rests with its stop pin 13 bearing 40 upon the frame and in this position the band 2 is out of frictional contact with the rotating drum 3 as indicated at 22 or bears so lightly thereon as to have no lifting effect upon the hammer. When, however, the

handle 4 is pulled down the controller 9 will be swung leftward, by the pull of the band 2, from the normal position shown, with the result that the band will press upon the surface of the rotary drum and the band 55 will then lift the hammer and continue doing so until the operator ceases to pull down

or relieves the handle 4, whereupon the hammer will drop and the sheath will be swung to the right into the normal position shown in Fig. 1, being arrested in this position 60 by the stop pin 13 coming against the frame and in this position the band 2 will be held substantially free from the surface of the revolving drum, which will no longer have a lifting effect thereon.

It is obvious that the point to which the hammer is lifted and consequently the length of its drop may be determined at the will of the operator who needs only to relieve the handle 4 of downward pressure 70 to cause the hammer to drop and thus the operator can make the hammer blows heavy or light as he may desire.

In order to positively establish slack in the band 2 so that a material portion of 75 said band will be brought in contact with the surface of the drum 3 before the lifting begins I provide a spring 14 which will create slack at 15 so that when the handle 4 is pulled down the sheath will swing 80 through a considerable angle before the band straightens out and therefore a considerable portion of the band will be in frictional contact with the drum before the lifting begins.

The form of sheath and the form and relation of the parts may be changed without departing from the principle involved in my invention. The stop pin holds the controller beyond the vertical center of its 90 pivot.

It will be understood that where herein I refer to operating the hammer by hand I do so in a generic sense to include other manual control such as by the foot.

In order to return the controller to its normal position with its stop pin 13 against the frame, I employ a spring 13^x connected thereto and to a suitable fixed point.

I claim:

1. In combination a drop hammer, a revolving drum, a band passing over the drum connected to the hammer and having a portion to be pulled upon by the operator, and a member mounted to have movement in a 105 direction circumferentially of the drum and engaging the band to normally free it from operative relation with the drum, said member when moved from normal position allowing the band to be operated by its frictional contact with the drum to raise the hammer, substantially as described.

2. In combination a drop hammer, a revolving drum, a band passing over the drum, attached to the drop hammer at one end and having a handle portion at its other end, 5 and a member of segmental form mounted to move circumferentially of the drum and arranged with its surface slightly beyond that of the drum, said member engaging the band to control its frictional engagement 10 with the drum, said member when in normal position with its band engaging portion over the top of the drum holding the band out of driving relation with the drum but moving circumferentially of the drum 15 when the operator pulls upon the handle portion of the band to cause the band to frictionally engage with and be driven by the drum, substantially as described.
3. In combination a drop hammer, a revolving drum, a band attached to the drop hammer and passing over the drum, a controller member pivotally mounted and engaging the band to release or allow its frictional contact with the drum, according to 20 whether said member is in normal position or is moved therefrom, said band having a handle portion to be pulled upon by the operator for swinging said member from normal position and bringing the band in contact with the drum to be driven thereby.
4. In combination a drop hammer, a revolving drum, a band attached to the hammer and passing over the drum, a controller member pivotally mounted and controlling 25 the effective engagement of the band with the drum and a stop for limiting the movement of the controller, said band having a handle portion to be pulled by the operator for swinging the controller from its normal 30 position and thereby permit the band to contact with and be driven by the drum, substantially as described.
5. In combination, a hammer, a revolving drum, a band passing from the hammer over the drum, a controller engaging the band, 45 and pivotally mounted on the shaft of the drum, said band having a handle portion by which the band may be pulled to swing the controller and thereby allow the band to contact with and be lifted by the drum, sub- 50 stantially as described.
6. In combination, a hammer, a revolving drum, a band passing from the hammer over the drum, a controller engaging the band, and pivotally mounted on the shaft of the 55 drum, said band having a handle portion by which the band may be pulled to swing the controller and thereby allow the band to contact with and be lifted by the drum said controller comprising arms and a cross piece, 60 substantially as described.
7. In combination, a hammer, a band, a drum over which the band passes, a controller for regulating the contact of the band with the drum, said band having a handle 65 portion which, when pulled, sets the controller in position to cause contact of the band with the drum, and means for creating slack in the band, between the controller and the hammer, substantially as described. 70
8. In combination, a hammer, a band, a drum over which the band passes, a controller for regulating the contact of the band with the drum, said band having a handle portion which, when pulled, sets the controller in position to cause contact of the band with the drum, and means for creating slack in the band, between the controller and the hammer, said means consisting of a spring connected to the band and the hammer, substantially as described. 75 80

In testimony whereof, I affix my signature.

WILLIAM A. KNAPP.
